UNITED STATES PATENT OFFICE.

SIMON B. MINNICH, OF LANDISVILLE, PENNSYLVANIA, ASSIGNOR TO MARY C. MINNICH, OF LANDISVILLE, PENNSYLVANIA.

TOBACCO-PRESS.

1,306,604.

Specification of Letters Patent. Patented June 10, 1919.

Application filed March 3, 1917. Serial No. 152,309.

To all whom it may concern:

Be it known that I, SIMON B. MINNICH, of Landisville, in the county of Lancaster and State of Pennsylvania, have invented certain Improvements in Tobacco-Presses, of which the following is a specification.

My invention relates to tobacco presses for compressing tobacco into receptacles. It is desirable to pack the leaves end to end and 10 where they vary in sizes boxes of different lengths are used.

My primary objects are to provide an expansible plunger and means for centering the plunger with relation to boxes of different 15 sizes.

In the drawings,

Figure 1 is a side elevation, and

Fig. 2 an end view.

Fig. 3 is a plan view of the plungers; 20 Figs. 4 and 5 sections on lines 4-4, 5-5, respectively, of Fig. 3.

Figs. 6, 7 and 8 are perspectives of the parts comprising the plunger.

Fig. 9 shows the means for centering the 25 box relatively to the plunger.

Fig. 10 shows a modified form of plunger, and

Fig. 11 is a section on the line 11-11, 30 Fig. 10.

Referring to the drawings, I have shown a press frame 1 having a cross-head 2 movable vertically in the frame and carrying a plunger 3. A weight 4 suspended from a rope passed over sheaves in the frame tends 35 to hold the cross-head and plunger elevated. In Fig. 1 a box is indicated at 5 and is shown in contact with a pair of side guides 6, preferably having rollers 6' vertically mounted thereon and slidably engaging the angle 40 irons 7 at the ends of the press frame. These guides may be locked in position by the lock bolt 6''. The plunger is drawn down by a pair of chains 8 connected to the cross-head and adapted to wind around a 45 shaft 9 having a lever 10 and a ratchet 12 governed by a pawl 13. The pawl is shown formed with a pedal 14 by which the operator may readily release it from engagement with the ratchet.

50 My improved plunger, in the preferred form of embodiment, is illustrated in detail in Figs. 3 to 8. As shown it comprises a central part or base 15 and end portions 16.

Each of the end portions is provided with 55 two or more bars 17 which are adapted to

slide through suitable brackets 18 as the end portions are moved toward or from each other. As appropriate means for operating the plunger parts I have shown a lever 19 fulcrumed on one of the brackets as at 20. 60 A rod 21 secured to one of the end pieces 16 is pivoted to the lever 19 at one side of the fulcrum 20 and a rod 22 is similarly attached to the other end portion and pivoted to the lever on the other side of the fulcrum 20. A 65 segment 23 is provided with perforations to receive a stud 24 on the lever 19. The spaces between these perforations may be so graduated that moving the lever sufficiently to place the stud into any one of the perforations will cause the end parts to be moved toward or from each other the desired distance so that the entire length of the plunger will exactly correspond with that of the box 70 within which it may be used. 75

I prefer to construct the plunger as shown in Figs. 3 to 8. As illustrated, the main portion has its width reduced at its extremities as at 25. The adjustable end members 16 are each made up of two parts and may have 80 their corners cut away in order that the plunger may descend into the box without coming into contact with the corner posts 5'. One part, 26, is adapted to move beneath the ends 25. It has upright flanges 85 27 at its sides to fit within the reduced extremities 25 and guide-blocks 28 on these flanges between which and the flooring the part 25 is received. The other member, 29, is of L-shape in cross section and is bolted 90 to the part 26 as at 30. This insures a durable structure not likely to become distorted or deranged and permitting of ready adjustment.

In Fig. 9 I have shown the means for centering the box or receptacle so as to assure its being held in alinement with the vertical movement of the plunger in whatever position the latter may be adjusted to. This view shows the guides 6 and guide rollers 100 6' and the lever 31 which is shown in side elevation in Fig. 1. This lever is mounted on a rocking shaft 32, slidably and rotatably mounted in suitable bearings 34, and which carries a stop 33 adapted to be held 105 in the proper position to arrest the movement of the box 5 of given dimensions so as to place it in direct alinement with the plunger. In the drawings I have shown how the stop 33 engages one corner of the 110

- box to limit its movement, the box entering the frame at the end of the frame opposite the stop 33. In a bracket 35 is shown a graduated plate 36 having a series of notches 5 corresponding to the graduations. The shaft 32 is adapted to rock responsive to the movement of the lever 31 and the latter carries a flange 37 which is adapted to engage any one of the notches in the graduated 10 plate. As illustrated the lever flange is in engagement with the notch appropriate for a box 39 inches long. If a larger box is to be used the lever is turned outward to release the flange from the notch in which it 15 may be seated and it is pushed inward to project the shaft 32 until the stop 33 shall have reached a more distant point. It will be understood that these graduations exactly correspond with those of the segments 20 23 so that correspondence between the point of location of stud 24 and flange 37 insures the plunger and the box being in correct alignment when the box is inserted over the roller 38. By merely rocking the lever 31 25 toward the center of the machine, the shaft 32 is rotated to swing the stop 33 downwardly out of the path of the box, to permit removal of the box from the opposite end of the press from which it entered.
- 30 In Fig. 10 I have shown a slightly modified form of plunger. The plunger comprises two main elements 40 and 41 adapted to overlap and to move in sliding engagement. They are suspended from the cross-head 2 by links 42 fulcrumed at each of 35 their ends and connected by a rod 43 having threaded engagement with blocks 44 secured in each of the links. This rod has a wheel 45 at its central portion and the threaded 40 engagement of the rod with one series of links is a right thread and the other a left thread. By this means the operation of the wheel may lessen or extend the angle of disposition of the links and in consequence 45 lessen or increase the extent of surface presented by the parts 40 and 41 of the plunger.
- I claim as my invention:
1. In a tobacco press, an expansible plunger adjustable to receptacles of various sizes, and an adjustable gage adapted to hold a receptacle in alinement with the path of travel of the plunger.
  2. In a tobacco press, the combination with an expansible plunger, of means for holding a receptacle in alinement with said plunger comprising a shaft, means for supporting said shaft, a stop carried by said shaft, a graduated plate having notches, a lever on said shaft adapted to move the 55 shaft longitudinally and having a flange to engage a predetermined one of said notches.
  3. In a tobacco press frame, the combination with an expansible plunger, of adjustable means for holding the ends of a receptacle in alinement with said plunger, and

means extending the length of the frame at either side of said receptacle for guiding it into position.

4. In a tobacco press, the combination with a plunger, of means for holding the ends of a receptacle in alinement with said plunger, adjustably mounted bars at either side of said receptacle, and rollers on said bars to form guides for the receptacle.

5. In a tobacco press, a frame, a plunger 75 adjustable to receptacles of various sizes movable in said frame, a guideway for guiding receptacles into alinement beneath said plunger, and a gage adjustable to receptacles of various sizes for stopping said receptacles 80 centrally beneath said plunger.

6. In a tobacco press, the combination with an expansible plunger, of means for holding a receptacle in alinement with said plunger comprising a shaft rotatably and slidably 85 supported in the press frame, a stop carried by said shaft, and a lever on said shaft adapted to move the shaft longitudinally and to rotate said shaft.

7. In a tobacco press, a frame, a plunger 90 movable in said frame, a guideway extending the length of said frame for bringing a receptacle beneath said plunger and adapted to receive receptacles at one end of said frame, a stop arm in said guideway for centering a receptacle beneath said plunger, and means for moving said stop arm out of the path of said receptacle to permit of the removal of said receptacle at the opposite 95 end of said frame.

8. In a tobacco press, the combination with an expansible plunger, of adjustably mounted side bars beneath said plunger for engaging a receptacle, and an adjustable stop for limiting the longitudinal movement of receptacles between said side bars.

9. In a tobacco press, a plunger comprising a body plate, end plates slidable toward and from each other upon the body plate to extend and contract the plunger and provide a substantially flat solid pressing surface, a lever fulcrumed upon the upper side of the body plate, link connections between the lever and end plates for adjusting the latter, and means carried by said lever for locking it in adjusted position.

10. In a tobacco press, a frame, a guide way in said frame adapted to receive receptacles of varying sizes, a cross-head movable in said frame, substantially vertical supports depending from said cross-head, and a plunger secured to said vertical supports adapted to be projected into the receptacles of varying sizes.

11. In a tobacco press, a frame, a cross-head movable in said frame, vertical supports depending from said cross-head, and a plunger adapted to be projected into receptacles of varying sizes comprising a main 125 pressing plate permanently secured to said 130

- supports and adjustable end plates carried by said main pressing plate.
12. In a tobacco press, a frame, a cross-head movable vertically in said frame, vertical supports carried by said cross-head, a plunger adapted to be projected into receptacles of varying sizes carried by said vertical supports, and means within the area of said plunger for adjusting the plunger.
13. In a tobacco press, a frame, a guide-way for said frame adapted to receive receptacles of varying sizes, and a plunger movably supported in said frame adapted to be projected into the receptacles.
14. In a tobacco press, a frame, a cross-head movable in said frame, vertical supports carried by said cross-head, an expansible plunger secured to said vertical supports adapted to be projected into receptacles of varying sizes and having a substantially flat and solid pressing surface, and a guide way in said frame beneath said plunger adapted to receive receptacles of varying sizes.
15. In a tobacco press, a frame, a cross-head movable in said frame, an expansible and contractile plunger adapted to be projected into receptacles of varying sizes comprising relatively slidable pressure plates, supports connecting said pressure plates with said cross-head, means mounted on the plunger and connecting the plates for effecting their relative sliding movements, and a guide-way in said frame beneath the plunger for receiving receptacles of varying sizes.
16. An adjustable plunger for presses, comprising a main pressing plate, end plates slidably supported on said main plate, guide
- bars on the end plates projecting over one surface of the main plate, guide-ways on said main plate for said guide bars, and means within the area of the plunger for moving said end plates relatively to the main plate.
17. In a tobacco press, an expansible and contractile plunger adjustable to receptacles of varying sizes, and means for receiving receptacles of varying sizes centrally beneath said plunger.
18. In a tobacco press, a frame, a cross-head movable in said frame, supports depending from said cross-head, an expansible plunger carried by said supports and adapted to be extended to substantially the inside area of the bottoms of the receptacles of varying sizes whereby the plunger may be projected into receptacles of varying sizes, means mounted on said plunger and within the area thereof for expanding the plunger, means in said frame for receiving receptacles of varying sizes beneath the plunger, and means for moving said cross-head to project the plunger into receptacles of varying sizes.
19. In a tobacco press, a frame, a guide way in said frame adapted to receive receptacles of varying sizes, an expansible and contractile plunger having a substantially flat and solid pressing surface adapted to be projected into receptacles of varying sizes and comprising relatively movable pressing plates, and means for moving said plunger into and out of the receptacles.
- In testimony whereof, I have hereunto subscribed my name.

SIMON B. MINNICH.
